WITNESS:

UNITED STATES PATENT OFFICE

LIVELY B. WILLOUGHBY, OF BOWLING GREEN, KENTUCKY

BISCUIT PACKAGE

Application filed January 31, 1925, Serial No. 6,101. Renewed February 13, 1930.

This invention relates to a method of and means for packing uncooked biscuits, the general object of the invention being to provide means for keeping the biscuits from contact 5 with each other and in circular shape when placed in a box.

This invention also consists in certain other features of construction and in the combination and arrangement of the several parts, to 10 be hereinafter fully described, illustrated in the accompanying drawings and specifically pointed out in the appended claim.

In describing my invention in detail, reference will be had to the accompanying drawings wherein like characters denote like or 15 corresponding parts throughout the several views, and in which:—

Figure 1 is a view of the biscuits placed in a box with the box in open condition.

20 Figure 2 is a view of the box wrapped ready for sale.

Figure 3 is a perspective view showing one biscuit with its protecting ring.

25 Figure 4 is a sectional view of Figure 3. The object of this invention is to provide means whereby uncooked biscuits can be sold so that all the buyer has to do is to bake the biscuits. After the biscuits are cut they are placed in a ring 1 of paraffined pasteboard or 30 the like, which not only holds the biscuit in shape but also prevents it from touching another biscuit when the biscuits are placed in a box, such as that shown at 2 in Figure 1. The box can be made of a size to hold the desired 35 number of biscuits, such as a dozen or a half dozen, and after the box is closed it is sealed by wrapping it up in oiled or other paper, as shown at 3 in Figure 2. Figure 4 shows the cardboard ring treated on its inner side with 40 paraffine, as shown at 4, though the entire ring can be treated if desired.

45 From the foregoing it will be seen that the uncooked biscuits are kept in proper shape and are prevented from sticking to each other by the rings and the sealed boxes will keep the biscuits clean and practically air tight so that they will keep for some time. All the consumer has to do is to place the biscuits 50 in the oven so that he is saved a great amount of trouble.

It is thought from the foregoing description that the advantages and novel features of my invention will be readily apparent.

I desire it to be understood that I may make 55 changes in the construction and in the combination and arrangement of the several parts, provided that such changes fall within the scope of the appended claim.

What I claim is:—

An article of manufacture, a narrow ring 60 formed of cardboard or the like and having its inner surface coated with paraffine, an uncooked biscuit, circular in shape, inserted in said ring with its sides in contact with the paraffine thereon, said biscuit and ring being 65 closed in a waxed wrapper.

In testimony whereof I affix my signature.

LIVELY B. WILLOUGHBY.
